SAFETY FOR DOUBLE ACTION TRIGGER
MECHANISMDavid L. Katz, Longmeadow, Mass., assignor to the
United States of America as represented by the Secre-
tary of the Army

Filed Dec. 14, 1960, Ser. No. 75,888

2 Claims. (Cl. 42—70)

(Granted under Title 35, U.S. Code (1952), sec. 266)

The invention described herein may be manufactured and used by or for the Government for governmental purposes without the payment of any royalty thereon.

This invention relates to firearms and more particularly to safety devices for preventing accidental discharge thereof.

In those firearms having inertia-type firing pins arranged for actuation against the primer of a chambered cartridge by a pivotal hammer, which is energized and released by a double-action trigger when pulled from a normal to a firing position, the hammer spring is deenergized when the hammer is in its normal forward position. Therefore, unless safety devices are provided, it is possible for an impact on the firearm to pivot the hammer sufficiently by its inertia to discharge a chambered cartridge.

In some such firearms, one safety device is provided to prevent any pivotal displacement of the hammer and another to prevent actuation of the trigger. This, obviously, is not suited to military-type firearms because it requires actuation of two safeties before a firearm is ready to be fired.

It is, therefore, one object of this invention to provide for firearms a plunger-type safety which blocks displacement of the firing pin until the safety is actuated for release thereof by the trigger when pulled to the firing position thereof.

It is another object of this invention to provide such a safety device which is simple and rugged in construction and positive in its operation.

The specific nature of the invention as well as other objects and advantages thereof will clearly appear from a description of a preferred embodiment as shown in the accompanying drawing in which:

FIG. 1 is a longitudinally cross-sectioned view of the firing mechanism of a firearm showing the hammer at rest in its forward position and the firing pin blocked against displacement by the safety;

FIG. 2 is a view similar to FIG. 1 but showing the safety actuated by the trigger to free the firing pin and the hammer released by the trigger to strike the firing pin;

FIG. 3 is an enlarged view taken along line 3—3 of FIG. 2; and

FIG. 4 is an enlarged and exploded perspective view of the firing pin and safety.

Shown in the figures is a shoulder-type firearm 12 having a breech housing 14 with a firing pin 16 longitudinally disposed therein. Firing pin 16 is actuatable against the primer of a chambered cartridge 18 by a hammer 20, which is pivotally energized and then released to strike the firing pin by means of a double-acting trigger 22 of conventional design when the trigger is continuously pulled from a normal to a firing position. Trigger 22 is pivotally mounted on a transverse pin 24 and includes a top surface 26 which extends rearwardly of the pin and thereby is displaced upwardly when the trigger is pulled to the firing position.

A coil spring 28 is disposed in cooperation with hammer 20 so as to be wound thereby when the hammer is swung rearwardly by trigger 22 during initial displacement thereof to the firing position. Whereby, hammer 20 is energized for striking firing pin 16 when released

2

from trigger 22 during the final displacement thereof to the firing position. Spring 28 is arranged so as to be deenergized when hammer 20 is adjacent a position for striking the rear end of firing pin 16.

Firing pin 16 is essentially cylindrical in configuration with a reduced diameter striker portion 30 at the front end and is provided with a flange 32 disposed adjacent the rear end. Flange 32 includes a semicircular portion, which extends radially from firing pin 16, and a substantially rectangular depending portion 34. Firing pin 16 is slidably mounted in a stepped bore 35 which also receives a coil spring 36 disposed between an annular shoulder 38 in the bore and the front side of flange 32. Whereby, firing pin 16 is biased rearwardly to a retracted position wherein striker portion 30 is completely withdrawn into bore 35. Bore 35 is enlarged at the rear end by a recess 37 to slidably accommodate flange 32 with its rectangular portion 34. Contact of the front end of flange 32 with the front end of recess 37 limits the forward displacement of firing pin 16. The rearward displacement of firing pin 16 is limited by a lock 39 which is transversely disposed across recess 37.

With hammer spring 28 being deenergized when hammer 20 is adjacent the striking position thereof, an impact against firearm 12 might, through inertia, cause sufficient pivotal displacement of the hammer to cause discharge of chambered cartridge 18. Therefore, there is provided a trigger-actuated safety 40 which releasably holds firing pin 16 against displacement until trigger 22 is pulled sufficiently for release of hammer 20.

Safety 40 is of plunger type and is slidably mounted in a vertical bore 42 which extends between recess 37 and a clearance 44 provided in breech housing 14 for trigger 22. The diameter of bore 42 is equal to the distance traveled by firing pin 16 between the retracted and forward positions thereof. More 42 is counterbored, as noted at 46, from clearance 44 to a shoulder 48.

Safety 40 includes a cylindrical head 50 having the same diameter as bore 42, a stem 52 of reduced diameter 40 and a cylindrical bearing 54 which has the same diameter as counterbore 46 so as to be slidably received thereby. Bearing 54 is provided with a semispherical follower 56 which depends axially therefrom and which is disposed for camming contact by top surface 26 of trigger 22.

Whereby, when trigger 22 is pulled from the normal to the firing position thereof, the pivotal displacement of the trigger is converted to translational displacement of safety 40. A coil spring 58 is disposed in counterbore 46 between shoulder 48 and the top side of bearing 54 to bias safety 40 downwardly to a firing pin blocking position. The downward displacement of safety 40 is limited by a stop pin 60 which is transversely disposed through breech housing 14 so as to intersect bore 42 at the upper end thereof and, thereby, is contactable by the underside of head 50. Head 50 is held by pin 60 in recess 37 so as to be contactable, as hereinafter described, by rectangular portion 34 of flange 32 for blocking forward displacement of firing pin 16 from the retracted position thereof.

A channel 62 of T-configuration extends longitudinally through rectangular portion 34 to free firing pin 16 for actuation to the forward position thereof when head 50 and the adjacent portion of stem 52 is aligned with the channel. Channel 62 includes a rectangular aperture 64 the cross-sectional dimensions of which are approximately the same as the silhouette of head 50 so as to be receivable thereby when in longitudinally aligned relationship. A passage 66 having the same width as the diameter of stem 52 extends between the aperture 64 and the bottom of rectangular portion 34 to provide clearance for such stem when firing pin 16 moves relative

to safety 40 and head 50 is received by such aperture. Channel 62 and passage 64 form lip portions 68 which are contactable by head 50 when safety 40 is disposed in the lower firing pin blocking position thereof and which are in registry with stem 52 when safety 40 is elevated to the firing pin release position wherein aperture 64 is in longitudinal alignment with such head. Safety 40 is actuated to the firing pin release position by the camming engagement of follower 56 with top surface 26 of trigger 22 when the trigger is pulled to discharge chambered cartridge 18. The relationship between follower 56, top surface 26, head 50 and aperture 64 is so arranged that the head is elevated into longitudinal alignment with the aperture immediately before the hammer 20 is released by trigger 22 after being energized thereby.

Thus, firing pin 16 is blocked at all times from being actuated against the primer of chambered cartridge 18 except when trigger 22 is manually pulled for discharge thereof. When trigger 22 is pulled, top surface 26 is raised against follower 56 of safety 40 which is elevated to the firing pin release position wherein head 50 is in registry with aperture 64, immediately before hammer 20 is released to strike firing pin 16. After chambered cartridge 18 is fired, hammer 20 is positioned at rest with spring 28 deenergized so that firing pin 16 is free to be actuated by spring 36 to its rearward position. Consequently, when trigger 22 is released to return to its normal position, safety 40 is lowered to its firing pin blocking position wherein head 50 is in blocking contact with lip portions 68.

From the foregoing it is clearly apparent that there is provided herein for firearms with a hammer actuated by a double-acting trigger and an inertia-type firing pin a safety device which prevents accidental action of the hammer against the firing pin, which safety device is simple in construction, positive in its functions and easy to manufacture.

Although a particular embodiment of the invention has been described in detail herein, it is evident that many variations may be devised within the spirit and scope

thereof and the following claims are intended to include such variations.

I claim:

1. In a firearm, the combination including a hammer pivotal between a retracted and a striking position, a spring disposed so as to be wound by said hammer during pivotal displacement thereof to the retracted position and de-energized when said hammer is adjacent the striking position, a firing pin arranged to be struck by said hammer for discharge of a chambered cartridge, a double-action trigger disposed for pivotal displacement between a normal and a firing position and so as to displace said hammer from the striking to the retracted position prior to release thereof during displacement of said trigger to the firing position, a plunger-type safety operatively disposed between said trigger and said firing pin for releasably blocking displacement thereof except when said trigger is displaced sufficiently to release said hammer therefrom, said safety being disposed for vertical reciprocation normal to the longitudinal axis of said firing pin between a firing pin blocking and a firing pin release position, a spring disposed for resiliently biasing said safety to the firing pin blocking position, and cooperating means operatively disposed on said safety and said trigger for actuating said safety to the firing pin release position when said trigger is displaced sufficiently from the normal position thereof to release said hammer.

2. The firearm as defined in claim 1 wherein said firing pin includes a flange having a longitudinally disposed channel therethrough and a pair of lips formed thereby, and said safety includes a head disposed for registry with said channel when said safety is in the firing pin release position and for contact with said lips when said safety is in the firing pin blocking position.
